KNITTING MACHINE

Robert H. Coleman and Osben D. Hunt, Hickory, N. C., assignors of one-fourth to Ernest E. Whisnant and one-fourth to Clarence L. Whisnant, both of Hickory, N. C.

Application December 7, 1939, Serial No. 307,964

13 Claims. (Cl. 66—135)

This invention relates to knitting machines. More specifically, it has reference to circular knitting machines of the type ordinarily employed in the production of seamless hosiery and the like with ornamental longitudinal wrap stripes or clocks formed from colored yarns upon predetermined needles which also take the yarn or yarns from which the body of the stocking is formed.

Wrap feed mechanisms heretofore designed for ornamental striping in machines of the kind referred to are highly complicated and therefore costly in their construction as well as liable to easy derangement; and moreover in most instances, they are mounted above the needle cylinders of the machines, as a consequence of which access to the tops of the cylinders for threading and other purposes is rendered difficult and time consuming. In addition to being complicated, the prior art wrap striping mechanisms are bulky and heavy, and so require considerable additional power for their actuation.

The chief aim of our invention is to overcome the above-mentioned drawbacks, which desideratum we realize in practice, as hereinafter more fully disclosed, through provision of a wrap striping mechanism which is of very simple and inexpensive construction, and in which a spindle with a plurality of circumferentially spaced eyes for delivering as many different striping yarns and arranged substantially at right angles to the cylinder is rotated in unison with said cylinder, the timing of the spindle being so ordered that the striping yarns are successively presented to predetermined striping needles located at corresponding points around the cylinder and elevated to a level higher than the remaining needles as they approach the striping feed.

In connection with a wrap striping mechanism having the foregoing attributes, it is a further aim of our invention to provide for the support and control of the feed spindle in such a manner that it will be moved out of operative position to interrupt the striping when desired or required, as for example during the knitting of the tops, heels and toes of the stockings, under governance of the usual cam drum of the knitting machine which determines the behavior of the interchangeable main yarn feeds.

Another object of our invention is to attain all the important above-recited advantages in a wrap striping mechanism having the form of an attachment which lends itself to ready incorporation in standard makes of circular hosiery knitting machines without entailing any changes

whatever in their construction or in their normal mode of operation.

Other objects and advantages of our invention will appear from the following detailed description of the attached drawings, whereof

Fig. I is a fragmentary view showing, in side elevation, a circular knitting machine conveniently embodying our invention.

Fig. II is a fragmentary view in plan section taken as indicated by the angled arrows II—II in Fig. I and drawn to a larger scale.

Fig. III is a vertical section drawn to a still larger scale and taken as indicated by the angled arrows III—III in Fig. II.

Fig. IV is a fragmentary detail view corresponding to Fig. III but on a larger scale, showing how the striping yarns are taken by the striping needles.

Fig. V is a fragmentary view in end elevation, looking as indicated by the angled arrows V—V in Fig. II and showing the mounting which carries the supply bobbins for the striping yarns together with the tensions and the take-ups whereby said yarns are controlled.

Fig. VI is a fragmentary detail sectional view taken as indicated by the angled arrows VI—VI in Figs. I and II.

Fig. VII is a fragmentary diagrammatic view looking as indicated by the angled arrows VII—VII in Fig. IV; and

Fig. VII shows a half-hose stocking with a wrap-clock stripe such as may be produced by the machine with our improved striping mechanism.

The circular knitting machine herein illustrated is generally of the well-known "Scott & Williams" type arranged for the production of half-hose, its cylinder 1 carrying an annular series of independent needles 2, and being revolvably supported in a bed plate 3 at the top of the machine frame 4. The needle cylinder 1 is rotated in the direction indicated by the arrows in Figs. II and VII in the usual manner, by drive means including a bevel gear 5 on the main shaft 6 of the machine. The cams generally indicated at 7 for vertically reciprocating the needles 2 are supported by a fixed supplemental bed or plate 8 suitably sustained above the main bed plate 3. As is customary in modern hosiery knitters, the machine is provided with a plurality of interchangeable main yarn feeds 9, 10, 11 and 12, which occupy a recess 13 in the arm 14 of the latch guard ring 15, and which are independently swingable about a transverse pivot pin 16 in said arm, so that they

can be individually moved into and out of action. Selection between the main yarn feeds is accomplished, through the medium of individually associated thrust rods whereof one is indicated at 17 in Fig. I, under the control of a cam drum 18 which is turned through a complete revolution for each stocking producing cycle of the machine. The drum 18 is rotatively shifted at intervals, also as well understood, by appropriate means not illustrated, under governance of the measuring chain of the machine indicated at 19 in Fig. I. The machine also has a supplemental cam drum 20 on a shaft 21 which is journalled in a fixed bracket 22 projecting from the frame 4, said drum 20 being intermittently rotated by a pawl 23 from the main shaft 5 of the machine under governance of suitable control mechanism (not illustrated) subject to the measuring chain 19. Pivoted for oscillation about a stud 24 on the bracket 22, are fingers 25 and 26 which ride 20 cam rises on the drum 20, and through connecting links whereof one is shown at 27, individually perform well-known functions with which the present invention is not directly concerned. For the purpose of selecting predetermined needles and raising them to a higher level above the remaining needles for striping, the machine is further provided with design pattern mechanism which is comprehensively designated 28 in Fig. I, and which includes a vertical axis drum 29 with 30 circumferential grooves for interchangeable pattern determining jacks (not shown). This needle selecting mechanism may be of the construction disclosed in U. S. Pattern No. 1,906,204 granted to A. E. Page on April 25, 1933, to which reference may be had for details if necessary.

The wrap striping attachment or mechanism of our invention, as herein delineated, comprises an auxiliary feed 30 which is positioned amongst the main yarn feeds 9—12 and connected to or integrally formed at the inner end of a spindle 31 whereof the axis extends substantially at right angles to the needle cylinder at the level of the tops of the elevated striping needles 2a (see Fig. III) and reaches outward from a point immediately adjacent the needle circle, said spindle being wholly external to said needle circle. As shown, the outer diametrically enlarged end 31a of the spindle 31 is journalled for rotation in a bearing 32 pivotally supported by a pair of pointed screw studs 33 and 34 in the opposite sides of a yoke member 35. This yoke member 35 has an internally threaded pendant shank 36 engaged by the threaded upper end of a supporting rod 37 which has a boss at its bottom end embracing the stud 24 on the bracket 22. By virtue of this arrangement, the bearing 32 may be adjusted vertically in setting up the wrap striping mechanism initially or afterwards as may be required, the adjustment being fixable by means of a jam nut shown at 38. A strut or tie bar 39 is employed to secure the yoke 36 against movement about the stud 24. From Figs. I and III, it will be observed that the strut bar 39 is connected at one end by a screw 40, to a post 41 whereon the latch ring 15 of the machine is pivoted, while its other end is slotted as at 42 for passage of the shank or a cap screw 43 which engages into one side of an upward extension 45 of the yoke member 35. Due to the provision of the slot 42 in the strut bar 39, it is possible to accurately adjust the auxiliary feed 30 toward and away from the needle circle. A spring 46 in tension between an anchorage 47 at the outer end of the bearing 32 and a screw 75

stud 48 on a lateral projection 49 at the top of the yoke 35, serves to normally hold the feed 30 down in its operative position with the outer end of said bearing abutting the bottom end of a stop pin 50 adjustable in said projection 49.

The means for rotating the auxiliary feed 30 in unison with the needle cylinder 1 in the direction indicated by the arrow above it in Fig. VII involves a system of gearing. As shown in Figs. II and III, this gearing includes a bevel gear pinion 51 which drives an intermeshing gear 52 on the spindle 31 and which is mounted for free rotation about a lateral cylindric bearing boss 53 on the yoke 35 in axial alignment with the pivot studs 33 and 34. For its further support, the pinion 51 is secured to a shaft 54 whereof the outer end is fixed in a sleeve 55 whereof the laterally-projecting screw shank 56 is engaged in a small bracket 57 on the yarn tree post 58 of the knitting machine. This arrangement permits the lateral adjustment of the pivot for the yoke 35 for the purpose already explained. In order that the sleeve 55 may be secured against displacement after adjustment, the screw shank 56 of said sleeve is fitted with a pair of jam nuts 59 and 60. Mounted on a rearward collar extension 61 of the gear pinion 51 is a sprocket wheel 62, which, by means of a chain 63, is connected to a sprocket wheel 64 on a shaft 65 extending radially of the needle cylinder 1 (see Fig. II) and forming an original part of the knitting machine. Also mounted on the shaft 65 is a bevel gear 66 in mesh with a bevel pinion 67 on a vertical shaft 68 which passes down through the bed plates 8 and 3, and is rotated by suitable connections (not shown) from the drive mechanism of the machine. The last described connections are like those disclosed in U. S. Patent No. 1,237,256 granted to Robert W. Scott on August 14, 1917. As illustrated in Figs. III, IV, and VII, the auxiliary feed has the form of a fork with diametrically arranged tubular tyne or prongs 69, 69' symmetrically disposed with respect to the axis of the spindle 31, which constitute guide eyes for delivering individual striping yarns W, W'. The yarns W, W' are respectively supplied from bobbins B, B' carried by a mounting in the form of disk 70 on the spindle 31, the bobbins being protected within enclosing cylindric casings of transparent material with telescoping parts 71, 72 and 73, 74 which are carried respectively by said disk and a cross member 75 secured by a screw 76 to the outer end of the spindle 31. Also supported by the disk 70 are slack take-up fingers 77, 78 which are subject to springs 79, 80 and which jointly, with spring tensions 81 and 82 at the ends of said cross member, respectively control the striping yarns W, W'. En route from the bobbins B, B', the wrap stripe yarns W, W' first pass to the tensions 81, 82 respectively, then around guide studs 83, 84 (Fig. V), then through openings 85, 86 in the cross member 75, then through the hooks of the take-ups 77, 78, then through guide tubes or ducts 87, 88 longitudinally recessed into the spindle 31, and finally emerge from the eyes 69, 69' of the feed 30.

Any suitable means may be provided to lift the auxiliary feed 30 out of action when desired or required, as during the knitting of the garter top G of each stocking S (Fig. VIII) as well as during the knitting of the heel H, the rear part of the instep I, and the toe T. The means herein illustrated for the purpose just referred to comprises a thrust bar 89 (Figs. I and III) which

is actuated by appropriately allocated rises (not shown) on the control drum 18, and which at its upper end is operatively connected, by a short link 91, with a laterally projecting arm 92 on the bearing 32 for the spindle 31.

Fixedly supported within the cylinder 1 at a level slightly below the normal upper level of the needle tops by a bracket 93 reaching inward from the latch guard ring 15, is a substantially circular plate 94 (see Figs. I and III), which ordinarily supports the means (not shown) for clamping and severing the main yarns as the latter are withdrawn from action. At the region directly opposite the feeds 10—12 and 30, the plate 94 is formed, in accordance with our invention, with an angular cam recess or notch for guiding and deflecting the wrap stripe yarns W, W', beneath said plate so that they are prevented from entangling with or wrapping around the clamping and severing means.

Assuming the pattern controlling mechanism 28 of the machine arranged to determine lifting variant numbers of needles above the others at diametrically opposite points in the cylinder 1 for the purpose of producing in the body portion of the stockings clock stripes at corresponding points such as shown at C in Fig. VIII, the operation of our invention is as follows:

As the cylinder rotates in the direction of the arrow in Fig. II, the hook of the raised striping needle designated 2a (which leads in the direction of rotation) passes transversely through the crotch in the forked end of the auxiliary feed 30 and encounters the striping yarn W as shown in Fig. VII, said yarn being anchored in the fabric at the point P (Figs. III, IV and VII) by the loop formed on said needle during the knitting of the preceding course. As the needle cylinder 1 continues in its rotation, the yarn W is wrapped about the needle 2a in the manner clearly shown in Figs. II, IV and VII, the other striping yarn W' being anchored at the other side of the fabric, and being positioned at this time above the raised needle 2a and is therefore not taken by said needle. As a consequence of the placement of the striping yarn W high on the shank of the needle 2a above the main yarn M delivered at this time by the main feed 11, the loops ultimately formed from said striping yarn by said needle 2a will appear at the face of the fabric in the narrow portion of the clock stripe C in Fig. VIII. Later during the same rotation of the needle cylinder, the wrap yarn W will be deflected as it encounters the edge 94a of the notch in the plate 94 and be depressed, and so prevented from entangling with the parts supported at the top of said plate. By the time the striping needle 2b at the opposite side of the cylinder (which is raised as it approaches the stitch point) reaches the feeding station, the striping yarn spindle 31, since it rotates in unison with the needle cylinder, will have turned through a half revolution, so that the other striping yarn W' is placed in a position to be taken by said needle 2b. The variations produced in the striping as the knitting continues, course after course, are determined by increases and decreases in the number of needles raised at opposite sides of the cylinder to take the striping yarns in accordance with the pre-arrangement of the jacks in the pattern drum 29 in a manner which will be readily understood by those skilled in the striping art. Just prior to the knitting of the heel portion H of the stocking, the auxiliary feed 30 is automatically swung upward

about the pivot screws 33, 34 under the control of the drum 17 and held out of operation until the completion of the heel when it is again restored to action for a time, likewise under the control of the drum 18, to extend the stripe part way into the instep of the stocking. In this connection, it is important to note that the turning of the spindle 31 will not be disturbed or changed since the gear wheel is coaxial with the pivot about which said spindle swings and moreover, since the drive relation between the spindle and the needle cylinder 1 is maintained by the sprocket chain which will readily flex without becoming detached from its sprockets during the swinging of said spindle. It is further pointed out that through the unison rotation of the spindle 31 with the needle cylinder 1, the wrap yarns W, W' will not twist about each other, and moreover during idling of this feed, the floats of said yarns will closely follow the opposite sides of the cylinder between the points of completion of the stripes in one stocking blank to the beginning of the stripes in a succeeding stocking blank. It also follows, for the same reasons that the floats of the striping yarns will not become entangled with the floats of the splicing yarns which are used to reinforce the high heels and the soles of the stockings.

From the foregoing, it will be evident that we have provided a wrap striping mechanism for circular knitting machines which is unique, not only from the standpoint of its simplicity, freedom from the possibility of easy derangement and its inexpensive construction, but in that it is applicable to standard makes of knitting machines without requiring structural changes in them or interfering with their normal mode of operation.

Throughout this specification, we use the term stripes to include clocks as only a special kind of stripe.

Having thus described our invention, we claim:

1. In a knitting machine having a rotating cylinder with an annular series of independent needles, driving means for the cylinder, a feed for delivering a main yarn to all the needles, and means for selecting predetermined single needles or groups of them for striping at circumferentially spaced points in the cylinder and causing them to travel at a level above the remaining needles as they approach the feed point; wrap striping mechanism including an auxiliary feed in the form of a spindle disposed substantially at right angles to the cylinder and wholly external to the needle circle, said auxiliary feed having, adjacent the needle circle, a plurality of circumferentially-spaced guide eyes for individual striping yarns which correspond in number to the single or groups of selected striping needles and which are equidistant from the spindle axis, and means for rotating the auxiliary feed in unison with the needle cylinder so that the respective striping yarns are successively taken by the single or group striping needles as the cylinder rotates.

2. A circular knitting machine according to claim 1, further including control means for automatically moving the striping yarn feed out of operative position relative to the needles when the striping is to be suspended.

3. A knitting machine according to claim 1, wherein the spindle of the wrap striping feed is journaled on a pivotally supported bearing; and whereon control means is provided for swinging the striping feed about its pivotal support to move

it out of operative position relative to the needles when the striping is to be suspended.

4. A knitting machine with wrap striping mechanism according to claim 1, wherein the spindle of the striping yarn feed has a mounting at the outer end of said shank carrying supply bobbins for the respective single or group striping yarns, together with tensions and take-ups for the individual striping yarns.

5. A knitting machine with wrap striping mechanism according to claim 1, wherein the spindle of the striping feed is journalled in a movable support for movement out of operative relation to the needles when the striping is to be interrupted; and wherein the spindle is rotated from the needle cylinder drive means of the knitting machine through interposed gearing which will allow movement of the striping feed as aforesaid without attendant change in its timing.

6. A knitting machine with wrap striping mechanism according to claim 1, wherein the spindle is journalled in a pivoted bearing to enable retraction of the striping yarn feed from its operative position relative to the needles when the striping is to be suspended; and wherein the spindle is rotated from the cylinder drive means through interposed gearing which includes a wheel rotatably mounted coaxially of the bearing pivot, so that the striping feed may be moved as aforesaid without attendant change in its timing.

7. A knitting machine with wrap striping mechanism according to claim 1, wherein the wrap striping feed is located amongst the main yarn feeds so that the main yarn or yarns and the striping yarns are taken by the striping needles at substantially the same time as said striping yarns.

8. A knitting machine with wrap striping mechanism according to claim 1, wherein the spindle is journalled in a pivoted bearing to enable retraction of the striping yarn feed from its operative position relative to the needles when the striping is to be suspended; wherein the spindle is rotated from the cylinder drive means through interposed gearing which includes a wheel rotatably mounted coaxially of the bearing pivot, so that the striping feed may be moved as aforesaid without attendant change in its timing; and wherein means is provided for adjusting the pivot for the bearing vertically to accurately position the delivery end of the striping yarn feed relative to the tops of the striping needles.

9. A knitting machine with wrap striping mechanism according to claim 1, wherein the spindle is journalled in a pivoted bearing to enable retraction of the striping yarn feed from its operative position relative to the needles when the striping is to be suspended; wherein the spindle is rotated from the cylinder drive means through interposed gearing which includes a wheel rotatably mounted coaxially of the bearing pivot, so

that the striping feed may be moved as aforesaid without attendant change in its timing; and wherein means is provided for adjusting the pivot for the bearing laterally of the cylinder to accurately position the delivery end of the striping yarn feed relative to the needle circle.

10. In a hosiery knitting machine having a rotating cylinder with an annular series of independent needles, a feed for delivering a main yarn to all the needles, and means for selecting predetermined needles for clock striping at diametrically opposite points in the cylinder and causing them to travel at a level above the remaining needles as they approach the feed point; wrap striping mechanism including an auxiliary rotary feed in the form of a spindle disposed substantially at right angles to the cylinder, the delivery end of said spindle being forked to provide diametrically spaced guides for delivering two different striping yarns, and means for rotating the spindle in unison with the cylinder so that the respective striping yarns are successively taken by the corresponding striping needles as the cylinder rotates.

11. A knitting machine with wrap striping mechanism according to claim 1, in which the feeding end of the spindle is of forked configuration and in which the tynes or prongs of the fork constitute the guide eyes for the respective striping yarns.

12. A knitting machine with wrap striping mechanism according to claim 1, in which the spindle has longitudinal ducts for passage of the individual striping yarns, and a forked feed end whereof the prongs or tynes are tubular and constitute the guide eyes for the respective striping yarns.

13. In a circular knitting machine for producing wrap stripes, the combination of a rotating needle cylinder and a main yarn feed, with a plurality of annularly arranged bobbins for individual striping yarns mounted to one side of said needle cylinder which are caused to rotate in synchronism therewith about an axis in substantially perpendicular relation to the needle cylinder, a correspondingly arranged series of feed eyes, one for each of said bobbins, which are also caused to rotate in said synchronism around said axis, the feed eyes when in feeding position being always outside the projected cylinder defined by the needles, and means to project selected single striping needles or groups of them from said needle cylinder at circumferentially spaced points to a position to successively receive the striping yarns, which, after having been caught by said needles, are wrapped around them for repeated knitting by the rotation of the needle cylinder alone.
